Collette

UNITED STATES PATENT OFFICE.

ALEXANDER R. COLLETTE, OF MINNEAPOLIS, MINNESOTA.

SIGNALING DEVICE.

Application filed June 22, 1923. Serial No. 247,119.

This invention relates to improvements in signal devices for street-cars, and the main object is to provide means for signaling other cars and vehicle traffic in the rear when the car is to stop to discharge passengers, and thus prevent rear-end collisions, protect passengers and save loss of time through unnecessary slowing up or stopping of traffic going in the same direction with the car. 5 Further objects will be disclosed in the course of the following specification, the invention being embodied and illustrated in the accompanying drawing, wherein:

Fig. 1 is a side elevation of a street-car embodying my invention.

Fig. 2 is a diagrammatic view of the electric circuit, the box B being shown in section.

Referring to the drawing more particularly and by reference characters, A designates a street-car having gates C, which are opened and closed by a crank D on a shaft E, operated by the motorman, and all of which are of common and well known construction.

20 Enclosing a portion of the shaft E is a box B, in which is arranged an electro-magnet F, and adjacent one end of the magnet F is a lever G, pivotally secured as at H, to the box, and adapted to oscillate between the magnet F and a stop or lug J. A spring K is connected at one end to the box and at its other end to the lever, and is so arranged that when the lever G moves from the magnet to the lug, or vice versa, the spring will 30 pass over the center H and will thus yieldingly retain the lever either against the lug or the magnet.

40 A wire 3 connects the lever G to a rear stop or signal light 4, which in turn is connected to a battery 5 by wire 6-7. A wire 8-9 runs from the other terminal of the battery 5 to a contact point 10, which, when touched by the lever G, completes a circuit through the elements G, H, 3, 4, 6-7, 5, 45 8-9 and 10.

One terminal of the magnet F connects with the wire 8 by a wire 11. The other terminal is connected by a wire 12 to a bell 13 in the motorman's compartment of the car. 50 The bell 13 is further connected in circuit with a series of passenger-operated push button switches 14, 15 and 16 by wires 17-18, 17-19, and 17-20, respectively, and the push buttons 14, 15 and 16 are further connected in circuit to the wire 7 by the respective wires 21, 22 and 23; thus completing a

60 circuit through the elements 7, 5, 8, 11, F, 12, 13, 17 and the connecting wires to the switch 14, 15 or 16, which happens to be closed.

The operation and use of the device may be briefly explained as follows:

When a passenger desires to leave the car at a certain street intersection he presses (for example) the button 15 upon approaching the intersection. This closes a circuit through the bell 13, thus signaling the motorman to stop the car, and also completes the same circuit through and energizing the magnet F. This pulls the lever G away 70 from the stop J and to the magnet, thus completing the circuit through and energizing the lamp or signal 4. When the passenger releases the button 15 the signal 4 will still be energized, as the spring K will keep the lever G in contact with the point 10.

75 The shaft E has a lug E¹, with a hinged-ly connected spring held tip or portion E², which slips over the lever G when the crank D is turned in the direction of the arrow D¹ 80 to open the gates. When the gates are to be closed, however, by turning the handle D in the direction of the arrow D², the member E² engages the lever G and, in passing, throws it over against the lug J, thus breaking the contact G¹⁰, and de-energizing the light 4.

85 It will thus be readily understood that when a passenger wishes to leave the car he pushes one of the push buttons, conveniently arranged for that purpose. This rings the bell 13, signaling the motorman, and also energizes the signal 4, notifying the vehicles going in the same direction that the car is to stop at the next intersection so 90 that the drivers of said vehicles may govern their actions accordingly.

95 The signal will, of course, stay energized until the motorman closes the gates, after 100 the passenger has been discharged, at which time the signal circuit will be automatically broken, and the traffic will be free to proceed.

105 It will be further understood that suitable modifications may be made in the device and the circuit arrangement, as herein set forth, provided, however, that such modifications are within the spirit and scope of the appended claim.

Having now therefore fully shown and 110 described my invention, what I claim to be new and desire to protect by Letters Patent is:

A car signaling system for a street car having a gate operating device, comprising a signal circuit including a stop signal and the armature of an electromagnetic switch, 5 means for yieldably holding the armature of said switch in either an open or closed position, an energizing circuit for the switch including a motorman's signal, a manually operable circuit closer, and the electromag-

net of said electromagnetic switch, means 10 operable by the gate operating device to trip over the armature of said switch, when it is moving in one direction, but, when moving in the opposite direction to engage the armature switch and move it from closed to 15 open positions.

In testimony whereof I affix my signature.

ALEXANDER R. COLLETTTE.
